(57) **CLAIM**

The ornamental design for a handlebar grip for hand tool, as shown and described.

DESCRIPTION

FIG. 1 is a perspective view of a handlebar grip for hand tool showing my new design;

FIG. 2 is another perspective view of the present design viewed from a bottom angle.

FIG. 3 shows a front elevational view of the present design, which is the same as the rear elevational view of the present design.

FIG. 4 shows a left side elevational view of the present design, which is the same as the right side elevational view of the present design.

FIG. 5 shows a top plan view of the present design.

FIG. 6 shows a bottom plan view of the present design.

FIG. 7 is a perspective view showing the handlebar grip of the present design equipped at its top with an accessory shown in broken lines, wherein the broken lines are for illustrative purposes only and form no part of the claimed design;

FIG. 8 is a perspective view showing the handlebar grip of the present design equipped at its bottom with an accessory shown in broken lines, wherein the broken lines are for illustrative purposes only and form no part of the claimed design; and,

FIG. 9 is still another perspective view of the present design viewed from another angle.
